UNITED STATES PATENT OFFICE.

ARTHUR A. McRAE, OF ATTLEBORO, MASSACHUSETTS.

DESIGN FOR A METALLIC FABRIC.

44,729.

Specification for Design.

Patented Oct. 14, 1913.

Application filed June 20, 1913. Serial No. 774,875. Term of patent 7 years.

To all whom it may concern:

Be it known that I, ARTHUR A. McRAE, a citizen of the United States, residing at Attleboro, in the county of Bristol and State of Massachusetts, have invented a new, original, and ornamental Design for a Metallic Fabric, of which the following is a specification.

In the accompanying drawing which forms a part of this specification the figure

is a front view of a metallic fabric embodying my design.

I claim:—

The ornamental design for a metallic fabric, as shown.

ARTHUR A. McRAE.
